UNITED STATES PATENT OFFICE.

FREDERICK W. BICKFORD, OF ROCHESTER, NEW YORK.

GARMENT-SUPPORTER.

SPECIFICATION forming part of Letters Patent No. 772,777, dated October 18, 1904.

Application filed July 26, 1902. Serial No. 117,070. (No model.)

To all whom it may concern:

Be it known that I, FREDERICK W. BICKFORD, of Rochester, in the county of Monroe and State of New York, have invented certain new and useful Improvements in Garment-Supporters; and I do hereby declare the following to be a full, clear, and exact description of the same, reference being had to the accompanying drawings, forming a part of this specification, and to the reference-numerals marked thereon.

My present invention has for its object to provide a garment-supporter adapted particularly for supporting dress-skirts and which may be worn about the waist and employed to form a means of connection between the skirt and dress-waist to hold both portions of the dress in position without interfering with the movement of the body of the wearer.

To these and other ends the invention consists in certain improvements in construction and combinations of parts, all as will be more fully described, the novel features being pointed out in the claims at the end of this specification.

In the drawings, Figure 1 is a perspective view of a garment-supporter constructed in accordance with my invention. Fig. 2 is an enlarged cross-sectional view. Fig. 3 is a view showing a band or tape upon which one or more of the devices may be applied, and Fig. 4 is a perspective view illustrating the application and operation of the device.

Similar reference-numerals in the several figures indicate similar parts.

A garment-supporter constructed in accordance with my invention is adapted to be secured about the wearer's waist and upon the exterior of the dress-waist, and it consists, preferably, of a plate 1, of light spring metal, provided with a central aperture 2, bounded at the upper side by a band 3, the lower edge of which is notched or serrated, forming teeth 4 thereon, and this edge of the band is struck up or bent toward the inner side or that side of the device which lies next to the wearer's body, as shown in Fig. 3. On the lower side the aperture is bounded by a similar but wider band 5, formed with a

tongue or extension 6, provided at its upper edge with the teeth 7, said tongue being bent outwardly, as shown, with the teeth thereon lying closer to the central line of the device than do the teeth 4. At the ends of the plate 55 1 are provided vertically-extending slits or apertures 8, which are formed by severing the material in the stamping-die in such a manner that small tongues 9 may be bent inwardly sufficiently to allow the passage of a band or tape 10 therethrough. While the material may be entirely removed to provide the apertures 8, I find it preferable to form them as shown, as the tongues 9, being bent more or less at an angle to the face of the 65 plate, form ribs thereon, materially strengthening the device and prevent its bending transversely, as might be occasioned by excessive strain upon the bands 3 and 5, and the tongues may also be bent downwardly to 70 lie more nearly in the plane of the plate 1 if it is desired to create more or less friction upon the band or tape and prevent the movement of the garment-holder thereon whether in operation or otherwise.

In operation a plurality of supporters may be used on the band or tape to secure the skirt and dress-waist at different points, and when in position the support is arranged with the narrower band 3, with the teeth 4 thereon, projecting inwardly. The narrower band 3 being at the top permits the plate to bend slightly longitudinally to conform to the curvature of the waist, while a corresponding curvature is also permitted the bar 5, owing 85 to the extended portions at the ends, containing the apertures 8, which are separated a slight distance from the ends of the tongue 6, so that while the band upon which the latter is formed may bend slightly the tongue 90 6 projects outwardly, so that as the device conforms to the waist the teeth 7 are not flattened, but project outwardly to permit the skirt-band to be engaged more readily therewith, as will be understood. This is an advantageous feature in that the band or tape 10 may be first applied with the projections 4 engaging the dress-waist and then tightened, which operation will tend to flatten the teeth 4, so that the inner face of the device 100

lies more or less smoothly in contact with the garment, but in secure engagement therewith.

The garment-supporter which I have shown and described may be easily formed from a sheet of light spring metal by the single operation of a stamp or die, and the devices being small a plurality of them may be employed, if desired. The particular arrangement and construction I have described is advantageous in that I am enabled to provide a number of comparatively fine teeth which enter the goods and firmly engage therewith without liability of straining or tearing the fabric.

15 I claim as my invention—

1. A garment-support embodying a plate provided with an aperture bounded at one side by a narrow band having projections upon its inner edge and extending at one side of the plate and having a similar band at the op-

posite side of the aperture provided with a tongue extending toward the first-mentioned band, and having projections thereon extending at the opposite side of the plate.

2. A garment-support embodying a plate 25 provided with a central aperture forming bands at opposite edges of the plate one of which is provided with teeth or projections and the other with an inwardly-extending tongue having similar teeth thereon said tongue and 30 the proximate edge of the other band being bent to project their teeth in opposite directions and lips severed at one edge transversely of the plate at its ends and bent to one side of the plate forming apertures therein.

FREDERICK W. BICKFORD.
